OPHTHALMIC LENS HARDENING APPARATUS

Stanley Kirk, Levittown, N.Y., assignor to Kirk Optical
Lens Co., Inc., Bronx, N.Y., a corporation of New York

Filed May 15, 1962, Ser. No. 70,141

Term of patent 14 years

(Cl. D54—8)

FIG. 1

FIG. 2

FIG. 3

FIG. 1 is a perspective view of an ophthalmic lens hardening apparatus, showing my new design;

FIG. 2 is an elevational view thereof taken from the side opposite that shown in FIG. 1; and

FIG. 3 is a rear elevational view thereof.

The bottom not shown is plain.

I claim:

The ornamental design for an ophthalmic lens hardening apparatus, substantially as shown and described.
